PICKUP TRUCK OR THE LIKE

Miklos Goldberger, 1663 20th St.,
Santa Monica, Calif. 90404

Filed Feb. 10, 1975, Ser. No. 548,771

Term of patent 14 years

Int. Cl. D12—08

U.S. Cl. D12—98

FIG. 1 is a perspective view of a pickup truck or the like embodying my new design;

FIG. 2 is a side elevational view thereof showing the side opposite to that shown in FIG. 1;

FIG. 3 is a top plan view thereof;

FIG. 4 is a rear elevational view thereof; and

FIG. 5 is a front elevational view thereof.

I claim:

The ornamental design for a pickup truck or the like, as shown.
